UNITED STATES PATENT OFFICE.

HARRY H. DE BOLT, OF MORGANTOWN, WEST VIRGINIA.

DESIGN FOR A HEADLIGHT HOOD.

Application filed August 15, 1927. Serial No. 23,097. Term of patent 14 years.

To all whom it may concern:

Be it known that I, **HARRY H. DE BOLT**, a citizen of the United States, residing at Morgantown, in the county of Monongalia and State of West Virginia, have invented a new, original, and ornamental Design for a Headlight Hood, of which the following is a specification, reference being had to the accompanying drawing, forming a part thereof.

Figure 1 is a side elevation of the headlight hood;

Figure 2 is a rear elevation of the headlight hood; and

Figure 3 is a top plan view of the headlight hood.

I claim:

The ornamental design for a headlight hood as shown.

HARRY H. DE BOLT.
